Primary Examiner — Brett Miller*Assistant Examiner* — Sara Michie Pottenger(74) *Attorney, Agent, or Firm* — Smith Tempel Blaha LLC; Matthew T. Hoots(57) **CLAIM**

The ornamental design for a gazebo keystone device, as shown and described.

DESCRIPTION

FIG. 1 is a top perspective view of a gazebo keystone device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the drawings depict portions of the gazebo keystone device. The broken lines form no part of the claimed design.
